TOOTH BRUSH

Martin E. Rudnick, 5848 McKellar Drive, San Jose, Calif.

Filed Apr. 24, 1961, Ser. No. 64,856

Term of patent 14 years

(Cl. D9—2)

Fig. 2.

Fig. 3

Fig. 4

Fig. 5

Fig. 6.

Fig. 7

Fig. 8

FIG. 1 is a perspective view of a tooth brush showing my new design.

FIG. 2 is a top plan view thereof.

FIG. 3 is a side elevation thereof.

FIG. 4 is a bottom plan view thereof.

FIG. 5 is an end elevation as seen from the left in FIGS. 3 and 1.

FIG. 6 is a sectional view taken through line 6—6 of FIG. 1.

FIG. 7 is a sectional view taken through line 7—7 of FIG. 1; and

FIG. 8 is a sectional view taken through line 8—8 of FIG. 1.

The dominant features of my design reside in the portions shown in full lines.

I claim:

The ornamental design for a tooth brush, as shown and described.
